CLAIM

The ornamental design for a two-sided hoe, as shown and described.

DESCRIPTION

FIG. 1 is a front, bottom-left perspective view of a two-sided hoe;

FIG. 2 is a front view of the two-sided hoe of FIG. 1;
FIG. 3 is a back view of the two-sided hoe of FIG. 1;
FIG. 4 is a back, bottom-left perspective view of the two-sided hoe of FIG. 1;

FIG. 5 is a front, bottom-right view of the two-sided hoe of FIG. 1; and,

FIG. 6 is an environmental perspective view of the two-sided hoe of FIG. 1 shown attached on the end of a handle.
The broken lines showing of the handle in FIG. 6 illustrates the environmental of the claimed design and form no part thereof.**1 Claim, 6 Drawing Sheets**| (56)	References Cited
